UNITED STATES PATENT OFFICE.

JOSEPH H. RUSBY, OF NUTLEY, NEW JERSEY.

ELECTRIC SWITCH.

1,269,121.

Specification of Letters Patent. Patented June 11, 1918.

Original application filed May 22, 1913, Serial No. 769,199; Patent No. 1,228,052, dated May 29, 1917. Divided and this application filed May 14, 1917. Serial No. 168,372.

To all whom it may concern:

Be it known that I, JOSEPH H. RUSBY, a citizen of the United States, residing at Nutley, county of Essex, and State of New Jersey, have invented new and useful Improvements in Electric Switches, of which the following is a specification.

The following invention is a division of my Patent No. 1,228,052, May 29, 1917.

10 The present invention relates to that class of surface type of electric switch which is essentially operated by push buttons to snap the blades into positive engagement with the contact devices.

15 The invention is designed to provide means for rotary adjustment of the switch to position it relative to the wall surface where it is secured.

20 The novel features of the invention are more fully described in the following specification and claims and illustrated in the accompanying drawing in which:

25 Figure 1 represents a front elevation of a surface type of electric switch showing the cover removed.

Fig. 2 is a vertical section taken along the line $z-z$ of the same.

Fig. 3 is a horizontal section taken along the line $y-y$ of the same.

30 Fig. 4 is a similar section taken along the line $z-z$ of Fig. 1.

Fig. 5 is a rear view of an insulated support.

Fig. 6 is a front elevation of one of the insulated supports.

Fig. 7 is a detail side elevation of the blades.

Fig. 8 is a side elevation of a make and break mechanism the blades having been removed.

Fig. 9 is a detail view of a push button.

Fig. 10 is a perspective view of a modified form of carrier piece.

Fig. 11 is a detail side view of a cover and armoring shell.

In this drawing the letter a designates an insulating supporting block preferably formed of porcelain with an open portion b and having chambers c , the object of which will be hereinafter described. The block as shown is constructed of two sections and fitted together. An armoring shell d is arranged about the exterior of the block and a plate 52 with holes for a pair of push buttons 25 is adapted to cover the front portion of the block. In the interior of the cover

and portions of the shell is located a lining 50 of mica or other non-conducting material. The armoring shell is secured to the blocks by means of lugs 51 coacting with recesses or seats e formed in the face of the block.

The make and break operating mechanism includes a pair of push buttons 25 having shanks pivoted at 26 to a spring actuating lever piece 27 mounted on a pivot bolt 28. The said bolt is supported in a frame 29, the front portion of which is adapted to be fastened by means of a screw 30 to the cover. A lug member 31 is mounted on the pivot 70 bolt 28 and it has connected to it a blade 32. Hard fiber or mica 33 insulates the blades from the remainder of the mechanism. A spring 34 is coiled about a drum 35 and this drum is mounted on a hollow spindle 39 75 fixed to the lever piece 27 noted above. A latch detent 36 is provided with a lug and it is pivoted at 37 to the supports. This latch is connected at 38 to the shank of one of the push buttons and the lug of the detent 80 coacts with one or the other of the edges formed on the rim of the blade carrier 31 mentioned above.

The lever piece 27 has a cross arm and the blade carrier 31 has a similar arm extending 85 between the shanks of the coiled spring. The lever piece 27 is operated by the push buttons and the blade carrier actuates the blades to snap into or out of engagement with the contact devices.

90 The conductor contact devices consists of a series of plates 40 with binding screws 41 threaded through the plates and extending into sockets formed in the face of the block. The conductor contacts 40 as shown are 95 formed of heavy metal to provide current capacity and stock for ample binding screw threads, while the blade contact portions 43 may be formed of thin metal of high conductivity such as hard drawn copper and secured upon the main contact as shown, thus obviating the need of springing the blades open widely which excessively wide springing tends to shorten the life of the blades by breaking, or of providing room for a thick 105 contact piece in the blade chamber c .

By constructing the spring drum 35 of drawn sheet metal and mounting it upon the hollow spindle 39 which spindle also carries the lever piece 27, a simplification is effected 110 and a reduction of metal weight, also a ready means of confining the operating spring by

turning back a lug upon the wall of the drum. As indicated in Fig. 4, the pivot bolt 28 has pointed ends bearing against the porcelain sides of the insulated block preventing 5 longitudinal play of the pivot and designed to form a pivot point with an insignificant degree of friction on the point. It should be said that the same result can be obtained by having the pivot riveted to the blade and 10 having a projecting point on the porcelain to center the pivot.

By forming the push button shanks with bifurcated ends 45 as shown in Fig. 9 a double support is formed for the rivet pin 15 26 thus saving switch depth space and adding strength.

As shown in Fig. 1, the means for adjusting the switch consist of screws 46 coöperating with the concentric slot 47 formed in 20 the insulated block *a*. The adjusting screw 46 has an angular head with a tapped portion arranged in the slot and a shoulder to bear against the rear portion of the block, a screw 48 is adapted to clamp the screw 25 46 to the block. By adjusting the screw 48 the switch may be turned around or rotated on the screw heads within the limits of the segmental slots to line the push buttons.

By extending the insulating base *a* of 30 the switch through the bottom of the armoring shell as shown at 49 and seating the switch upon this insulating base, a space for air insulation is provided between the armoring shell and the wall support in case 35 the blade insulation breaks down and it also prevents shifting of the insulating base *a* in the shell.

By turning in the lugs 51 on the armoring shell top upon the seats *e* in the insulating base, this base is securely clamped into the shell, regardless of any additional securing means.

By extending the ends of the flexible shell lining insulation under these turned-in lugs 45 before the lugs are turned, the lugs also secure the flexible insulation 50 into place.

The turning in of these lugs on the armoring shell *d* also provides slots for turning a series of lugs *f* on the cover plate 52, 50 as denoted in Fig. 11, preventing any shifting of cover plate which might bind the push buttons 25 and prevent freedom of action.

The sheet insulation 50 provides separation of the contact piece from the shell.

The frame lugs 29 as indicated in Figs. 1 and 2 for inclosing the push buttons, prevent swing of the metal button shanks over against live metal parts such as contacts.

60 The riveting of flexible spring contacts 43 as shown in Fig. 3 upon the conductor contacts 40 economizes space, and provides positive electrical conductivity.

By forming the blade carrier 31 in two 65 parts, as shown in Fig. 10, great strength

and rigidity are obtained, while allowing the carrier piece proper to extend up for efficient blade rivet support, while the latching lug is braced to great mechanical stiffness. By bending in the ends of this lug 70 31 of the blade carrier, they can be formed to clear the blade by ample insulating space, and at the same time form stops against the shell bottom.

By shouldering the inside pivot 28 upon 75 which these blade carriers 31 and 39 are mounted, with double riveting shoulders, the carrier can be riveted upon the first one and the remaining one may form a securing rivet support for the blade, and a preventive 80 of longitudinal play as noted previously.

It will be readily understood that the switch can be adjusted as to the depth in a wall by means of the devices 46 and 48. In this construction, the screws 46 can coact 85 with a wall box and are run in or out as to the depth required. The necks of the screws 46 are squared to fit the slots 47 as indicated in Fig. 5, so that when the screws 48 are in engagement with the square heads 90 the screws cannot turn. These adjusting screws are adapted to clamp the switch onto a surface or into a wall box as desired.

I claim:

1. An electric switch comprising a metal 95 receptacle, an insulating supporting block seated in said receptacle, said insulating supporting block being extended through the bottom of the said receptacle to form mounting seats for said switch, to retain a 100 separation between said receptacle and mounting surface, and to assist in securing said insulating block in said receptacle.

2. An electric switch comprising a metal 105 receptacle, an insulating supporting block in said receptacle, said insulating supporting block being provided with seats, said receptacle having lugs turned over into said seats for securing said insulating supporting block in said receptacle.

3. An electric switch comprising a metal 110 receptacle, an insulating supporting block in said receptacle, sheet insulation between said contacts and said receptacle wall, lugs on said receptacle wall turned in over said flexible insulation for retaining said insulation in said receptacle.

4. An electric switch comprising a metal 115 receptacle, an insulating supporting block in said receptacle, said insulating supporting block being provided with seats, said receptacle having lugs turned into said seats, slots in said receptacle wall formed by turned in lugs, and a cover plate, said cover plate provided with lugs adapted to 120 seat into said slots for retaining said cover plate circumferentially fixed.

5. An electric switch comprising a support, contacts and a make and break mechanism, said mechanism comprising a verti- 130

- cal supporting frame, a hollow pivot support mounted horizontally upon said frame, a pivot bolt inside said hollow pivot support, said bolt having a shouldered neck of 5 reduced diameter, a blade carrier secured thereby upon said pivot bolt, and a secondary shouldered neck of still further reduced diameter, and a blade secured thereby upon the smaller shouldered neck.
- 10 6. An electric switch comprising a support, contacts and a make and break mechanism, said mechanism including a vertical supporting frame, a hollow pivot support mounted horizontally upon said frame, a 15 pivot bolt in said hollow pivot support, a blade and a blade carrier mounted concentrically upon said pivot bolt, said blade carrier comprising two portions, one portion extending vertically, the other portion extending horizontally and supported upon 20 said vertical portion above said pivot support, said vertical portion extending above said supporting junction for supporting said blade.
- 25 7. An electric switch comprising a metal receptacle having a base, an insulating supporting block, contacts and a make and break mechanism, said mechanism comprising a supporting frame, said frame mounted 30 upon said receptacle base, and said insulating supporting block mounted in said receptacle independently of said supporting frame.
- 35 8. An electric switch comprising a base, contacts and a make and break mechanism, said mechanism comprising a vertical supporting frame, a lever pivoted upon said frame, push buttons pivoted upon said lever, said frame having lugs inclosing said push 40 buttons for confining same horizontally.
- 45 9. An electric switch comprising an insulating supporting block, contacts, an armoring shell about said block, and a make and break mechanism, said mechanism comprising a vertically extending supporting frame, a blade carrier pivoted upon said frame, said carrier adapted to stop against the base of said armoring shell.
- 50 10. An electric switch comprising a receptacle, an insulating supporting block, contacts, and a make and break mechanism, said block having a concentric securing slot 55 for supporting means, said slot being elongated circumferentially of said switch center for adjustment on said supporting means.
- 60 11. An electric switch comprising an insulating support, a make and break mechanism, said mechanism comprising a blade, and a conductor contact formed of relatively thick metal, said contact forming a support for a thinner contact adapted to connect with said blade.
12. An electric switch comprising an insulating support, a make and break mechanism, said mechanism comprising a blade, and a contact supported upon said insulating support, said contact having a shoulder, and a spring contact secured upon said contact shoulder, adapted to connect with said 70 blade.
13. An electric switch comprising a receptacle, an insulating supporting block, contacts, and a make and break mechanism, said block having a concentric securing slot 75 for supporting means, said slot elongated circumferentially of said switch center for adjustment on said supporting means, said supporting means comprising a screw with a shouldered head to seat into said elongated slot against rotation, said shouldered head having a tapped hole for securing screw.
14. An electric switch comprising an insulating supporting block, contacts, and a 80 make and break mechanism, said block having a concentric securing aperture for the supporting means, said supporting means including a screw, a shouldered head on said screw to fit into said aperture against 85 rotation, said shouldered head having a tapped hole for the securing screw.
15. An electric switch comprising an insulating supporting block, contacts, and a 90 make and break mechanism, said mechanism comprising a vertical supporting frame, said frame mounted upon said receptacle base, and said insulating supporting block mounted in said receptacle independently of said supporting frame, said frame 95 having a horizontal bend at top and a tapped hole, said switch provided with a cover having a supporting hole, and a supporting screw in said hole, adapted to thread into said tapped hole in said frame 100 top.
16. An electric switch comprising a metal receptacle having a base, an insulating supporting block in said receptacle, a depression in said block, contacts, and a make and break mechanism secured upon the base of said receptacle in said depression, said mechanism comprising a vertical supporting frame, a tubular pivot support horizontally on said frame, a pivot in said pivot 105 support, a blade carrier on said pivot and a blade on said carrier, and means whereby said insulating block confines said pivot against longitudinal movement.
- 110 In testimony whereof I have hereunto 120 set my hand in the presence of two subscribing witnesses.

JOSEPH H. RUSBY.
